UNITED STATES PATENT OFFICE.

FREDERICK FOSDICK, OF FITCHBURG, MASSACHUSETTS.

PISTON-VALVE.

SPECIFICATION forming part of Letters Patent No. 323,410, dated August 4, 1885.

Application filed June 16, 1884. (No model.)

To all whom it may concern:

Be it known that I, FREDERICK FOSDICK, of Fitchburg, county of Worcester, and State of Massachusetts, have invented an Improvement in Piston-Valves, of which the following description, in connection with the accompanying drawings, is a specification, like letters on the drawings representing like parts.

My invention, relating to piston-valves for steam-engines, is shown as embodied in an engine having a valve-gear, cylinder, and steam-chest such as shown in Letters Patent No. 279,404, granted to me June 12, 1883, the said patent showing independent piston-valves controlling inlet-ports at the ends of the cylinder, and being themselves operated by a wrist-plate valve-gear.

When piston-valves are employed, it is desirable to provide means for adjusting the said valves diametrically, so that they may be made to fit their valve-cylinders after the surfaces have worn away, and such adjustment has heretofore been provided for in some cases by making the periphery of the valve as a cylindrical shell split longitudinally at one side and having a tapering bore at its inside cooperating with a tapering plug, which by its longitudinal movement expands the shell to compensate for the part worn away, thus causing it to fit the cylinder properly. I have found that the valves of this class having an expansible outer shell become expanded when in operation by the pressure of steam within the said shell, thus causing them to fit too tightly in the cylinder, so as to produce a large amount of friction and require a large pressure to move them. Such expansion of the valve is obviated in accordance with the present invention by tapering the ends of the expansible shell and giving to the heads of the valve a corresponding taper, so that when the said heads are bolted tightly upon the ends of the valve the outer shell of the latter is positively locked in its adjusted shape and size, and cannot be expanded by internal steam-pressure. When it is to be expanded by the tapering plug for the purposes of adjustment, the heads are first loosened, and then, when the valve is properly adjusted, they may again be bolted tightly upon the ends thereof to prevent further expansion.

In engines employing a governor by which

the valve-actuating eccentric is moved across the shaft to change the point of cut-off, and thus control the power applied to the engine, 55 the travel of the valve is diminished as the point of cut-off is made earlier and its speed of movement is reduced, so that a less extensive opening is afforded for admission of steam to the cylinder, and the steam is likely to be 60 wire-drawn or to enter the cylinder at a less pressure than in the steam chest and boiler. This is obviated in accordance with the present invention by providing a longitudinal passage in the periphery of the piston-valve, so 65 arranged with relation to the inlet-port of the cylinder and to the passage in which the valve travels that when the said valve begins to uncover the port and admit steam over one edge thereof the said passage will connect the 70 inlet-port with the steam-spaces at the other side thereof, thus admitting steam from both sides of the inlet-port simultaneously and giving double the opening that would be obtained by a piston-valve without such longitudinal 75 passage.

Figure 1 is a plan view, partly in section, of a portion of an engine containing valves embodying this invention; Figs. 2 and 3, longitudinal sections on lines *x x* and *y y*, respectively, of Fig. 4 of the valve proper on a larger scale; Fig. 4, an end view of the said valve, and Fig. 5 a transverse section thereof on line *z*, Fig. 3.

The chest *a* containing live steam, the inlet- 85 ports *b b'*, leading therefrom to the ends of the cylinder, and the valve-gear, a portion of which is shown at *c c'*, for operating the valve-stems *d d'* connected with the valves *e e'*, may all be of usual construction, being connected 90 in this instance substantially the same as shown in my former patent referred to, the steam-chest containing passages *f f'*, connecting the steam-spaces at opposite ends of each of the valves *e e'*, so that the pressure on the said 95 valves is balanced independently, as described in the said patent, and the valve-stem *d* being tubular and surrounding the stem *d'*.

The valves *e e'*, as shown in Figs. 2 to 5, are composed of an outer shell, *g*, split longitudinally at one side, as shown at 2, and having its interior made tapering, as shown in Figs. 2 and 3, and containing a bushing, *h*, which is also longitudinally split, preferably

on the opposite side of the valve from the split in the shell g . The said bushing contains a tapering plug, i , which, when forced longitudinally into the said bushing and shell, will 5 expand the latter, increasing its external diameter, and thus enabling it to be adjusted to compensate for wear.

The outer shell, g , bushing h , and plug i are held in proper relation to each other and joined 10 with the valve-stem d or d' by means of a sleeve, k k' , fitted upon the valve-stem and securely held thereon between a projection or shoulder, d'' , on the said stem and nuts d'' , the said sleeve being made in two parts to enable 15 it to be inserted in the plug i' from opposite ends thereof. The part k of the sleeve is provided with a flange or head, k^2 , which overlaps the end of the shell g , the joint between the end of the shell and the head being made 20 tapering or inclined, as shown, so that when the head is pressed tightly upon the end of the shell it locks, the latter preventing it from expanding further. The other end of the valve is provided with a corresponding head, k^3 , free 25 to slide longitudinally upon a flange on the portion k' , and the said head k^3 is drawn toward the head k^2 to embrace and tightly hold the shell g between the said heads by means of bolts m (see Fig. 3) passing longitudinally 30 through the plug i' . The head k^3 and adjacent end of the shell g are tapered the same as the head k^2 , so that when the said heads are drawn tightly together upon the shell they lock the latter securely from expansion.

35 The plug i is moved longitudinally to expand the shell and adjust the diameter of the valve by means of bolts and set-screws n n' passing through the head k^3 and engaging the adjacent end of the said plug, which thus 40 may be moved to a greater or less distance from the said head k^3 , this being done while the bolts m are loosened, and when the said bolts are subsequently tightened, drawing the head k^3 toward the head k^2 , the plug i will 45 wedge into the shell g , expanding the same until it is engaged and locked by the two heads bearing solidly against it, when the said heads constitute a locking device, preventing the shell from expanding further or away from the 50 plug i .

The shell g is provided with a longitudinal passage, o , just within its circumference, as best shown in Figs. 3 and 5, the portion of the periphery of the valve-shell which the 55 said passage underlies being supported by bridges o' , Figs. 2 and 5. The said passage operates, as best shown in Fig. 2, to admit steam from the side of the steam-chest toward which the valve is moving in opening 60 or uncovering the inlet-port b through the said passage to the port b and cylinder, as

shown at 2, at the same moment that the valve uncovers the opposite edge of the port at 3, admitting steam directly from the steam-chest, thus affording double the width of opening for 65 the admission of steam that would be provided if the valve did not have the passage o' and controlled the admission of steam only over the edge 3 of the port.

The length of the passage o is proportioned 70 to that of the bridge between the port b and the edge 2 of the cylindrical passage in which the valve operates, so that the valve admits steam at 2 and 3 at the same moment.

Both valves e e' are the same in construction, and have the same relation to the ports controlled by them, and the valve e' is fixed upon the solid rod d' in the same manner that the valve e is fixed upon the tubular rod d surrounding the rod d' . 75

Access may be had to the nuts of the fastening-bolts m and the adjusting-bolts and screws n n' , for the purpose of adjusting the valves when they have worn loose by removing the heads or bonnets a' of the steam-chest, 85 which is shown in Fig. 1, with one bonnet thus removed.

I claim—

1. In a piston-valve for steam-engines, the combination, with an expansible shell having 90 tapering or conical ends and tapering plug co-operating therewith, of heads engaging the ends of the said shell, the faces of the said head which engage the ends of the said shell being tapering, whereby the shell, when adjusted by the plug, is prevented from further expansion, substantially as described.

2. In a steam-engine, the steam-chest a , having ports b b' leading therefrom to the cylinder and steam-passages connecting the steam-spaces at opposite ends of the valve-heads, combined with a piston-valve acted upon at each end by live steam, the valve being provided with openings surrounding it at different portions of its length, such openings being 105 united by longitudinal passages o , whereby steam is admitted alternately into the ports b b' at two places simultaneously, substantially as described.

3. The expansible shell and expanding device for adjusting the same as to external diameter, combined with the locking device positively engaging the said shell; preventing further expansion thereof after the said shell is properly adjusted, substantially as described. 110

In testimony whereof I have signed my name to this specification in the presence of two subscribing witnesses.

FREDERICK FOSDICK.
